UNITED STATES PATENT OFFICE

128,298

DESIGN FOR A PAPER CLAMP

Lawrence L. Houser, Mishawaka, Ind.

Application April 15, 1940, Serial No. 91,683

Term of patent 7 years

To all whom it may concern:

Be it known that I, Lawrence L. Houser, a citizen of the United States, residing at Mishawaka, in the county of St. Joseph and State of Indiana, have invented a new, original, and ornamental Design for Paper Clamp, of which the following is a specification, reference being had to the accompanying drawing, forming a part thereof. The single figure of the drawing is a front perspective view of a paper clamp embodying my design.

My design for a paper clamp, as illustrated, is characterized by a relatively straight top por-

tion with slight bend in the center thereof, having legs which extend inwardly and downwardly, forming a triangular shape, then interlocking each other and extending downwardly again and outwardly, and being provided with small looping portions and then again extending downwardly with the ends of said legs being bent outwardly so as to form right angles.

I claim:

The ornamental design for a paper clamp, as shown and described.

LAWRENCE L. HOUSER.
